FIG. 1 is a front, right and top perspective view of a washing machine for fruit and vegetable, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken lines shown in the drawings are included for the purpose of illustrating portions of the washing machine for fruit and vegetable that form no part of the claimed design.

1 Claim, 7 Drawing Sheets
